UNITED STATES PATENT OFFICE.

JAMES S. HARDIMAN, OF LONG ISLAND CITY, NEW YORK, ASSIGNOR TO ANCHOR CAP AND CLOSURE CORPORATION, OF LONG ISLAND CITY, NEW YORK, A CORPORATION OF NEW YORK.

UNCAPPING TOOL.

Application filed July 7, 1925. Serial No. 41,939.

This invention relates to uncapping tools and the like, and particularly to an uncapping tool or opener peculiarly adapted for opening containers sealed under a vacuum with a relatively large diameter closure which is side sealed to the container.

Heretofore in the art, various types of leverage devices have been proposed for removing sealing caps from containers. Some 10 of these prior art devices have been made of cast metal, and have consisted of a handle, a fulcrum portion, and a cap engaging member, the last two parts being necessarily of such small size that they had little strength 15 and rendered the casting of the tool difficult and expensive. It has also been suggested that devices of this character be made from wire, but wire devices are not suitable for opening relatively large sized packages such 20 as jelly jars and the like, especially when sealed under a vacuum, because of the limitations on the shapes of wire devices, and also because of the lack of strength and 25 rigidity of wire of the size which could be used for the purpose.

In the prior art, openers have also been stamped from sheet metal but these openers have either been of comparatively complicated forms which were relatively expensive and difficult to manufacture, or have been 30 of forms which do not have sufficient strength and rigidity for removing large sized closures. One form of prior art opener consists of a flat piece of metal comprising a fulcrum portion, a cap engaging jaw and a ring through which the user inserts 35 his finger in manipulating the opener. This type of opener is not suitable for removing large closures which require the application of a large uncapping force, for the reason 40 that such openers are much too weak and flexible to apply the requisite force, and for the further reason that it is difficult for the user to exert much force by pulling with one 45 finger.

The present invention overcomes the difficulties of the known prior art by providing a stamped sheet metal opener, comprising a substantially flat body portion having integral therewith a fulcrum member, a cap engaging jaw and reinforcing flange which 50 extends along the fulcrum member, passes around the entire opener, and terminates at the cap engaging jaw, thereby stiffening and

strengthening the entire opener. This construction enables the opener to be made of very light weight sheet metal and still have sufficient strength and rigidity to adapt it for removing large sized closures sealed to a container under a vacuum. The form of 55 the opener is such that it can be manufactured by a simple stamping operation, thus enabling it to be manufactured at an extremely low cost.

The principal object of the present invention is an uncapping tool, or the like, having a flat edgewise disposed body portion carrying a reenforced cap engaging jaw and a reenforced fulcrum member integral with the body portion. 65

Another object of the present invention is a sheet metal uncapping tool having a relatively flat body portion terminating at one end in a fulcrum extension and a cap engaging jaw, and having a reinforcing flange 75 extending around the outer boundary of the opener.

Another object of the present invention is to provide a strong, inexpensive, and readily manufactured uncapping tool particularly adapted for removing side sealed 80 closures from jelly glasses and the like.

Other objects of the present invention will be obvious from the following description.

Fig. 1 of the drawings is an elevational view showing a tool embodying the present 85 invention, and the manner of using it in opening a well known type of side sealed package.

Fig. 2 is an enlarged perspective view 90 illustrating the operating end of the opener.

Fig. 3 is an elevational view of the tool showing the reverse of the side shown in Fig. 1.

Fig. 4 is a perspective view of the flange 95 side of a modified form of opener.

Fig. 5 is an elevational view showing the reverse side of the opener shown in Fig. 4.

As shown in Figs. 1, 2, and 3 of the drawings, the preferred embodiment of the invention is stamped from a single piece of sheet metal, and comprises a flat body portion 1 having a rounded rear end 2 and an operating end which comprises a fulcrum 4, and a cap engaging jaw 5. The face of the fulcrum 4 comprises a flange 3 which gradually increases in width from the cap receiving recess 6 until it merges into a rounded nose 100 105

at 7. This flange is carried around the entire outer edge of the cap opener and terminates at the cap engaging jaw 5 thus reenforcing the jaw and stiffening and reenforcing the entire tool.

As clearly illustrated in the drawings, the cap engaging jaw is inclined downwardly toward the recess 6. As shown in Fig. 1, this permits the forward edge of the jaw to engage the gasket 8 at a point contiguous to the container 9, thus enabling the tool to get a firm bite on the gasket and pull the entire gasket and bead of the cap upwardly and outwardly. The wide flange 3 of the fulcrum 4 provides adequate bearing surfaces on the top of the cap; and this together with the rounded nose 7 enables the user to remove the closure in a positive clean cut manner instead of denting and mutilating the top of the cap. By reason of the flat flange 3 of the fulcrum member 4 and the flat edge 10 of the cap engaging jaw, the opener is firmly wedged in position during the opening operation, thus preventing it from rolling in the hand of the user.

Beneath the cap engaging jaw is a comparatively large section of metal 12 which firmly supports the jaw and serves to transmit the opening forces to the handle portion 1. The rounded rear end 2 is preferably provided with a hole 13 which may be used to hang up the tool, and preferably this hole is made quite large in order to reduce the weight of the tool and thus save shipping expense when the openers are shipped in bulk.

The form of the invention shown in Figs. 3 and 4 is that disclosed in my prior copending application 24,738, filed April 21st, 1925, of which the present application is a continuation in part. This form of the opener is similar to that disclosed in Figs. 1 to 3 except that it is not provided with a rounded nose and the cap engaging jaw is not downwardly inclined. This form of the opener comprises a flat body portion 20, having an operating end comprising a fulcrum 21 and a cap engaging jaw 22. The face of the fulcrum 21 comprises a flat face 23 which gives adequate bearing surface on the top of the closure. The entire opener is stiffened and reenforced by a flange 24 which starts at the end of the fulcrum, passes around the entire opener and terminates in an edge 25 extending perpendicularly from the jaw 22.

In the form of opener shown in Figs. 1 to 3, the reenforcing flange is on the left hand side of the tool, while in the form shown in Figs. 4 and 5, the flange is on the right hand side of the tool. It is obvious that either form of tool may be made with flange on either side, but it is preferable to place the flange on the left hand side, as in Figs. 1 to 3, if the opener is to be manipulated with the right hand, and vice versa.

This places the flat side of the opener against the palm of the hand which is the more comfortable position.

It is realized that the present invention may be embodied in forms other than those particularly disclosed herein, and hence it is desired that the present disclosure be considered as illustrative and not as limiting.

Having thus described my invention, what I claim is:

1. In a tool of the class described; an operating end comprising a flat edgewise disposed fulcrum member provided with a rounded nose; a reenforcing flange integral with said fulcrum member and extending at right angles therefrom, said flange extending along the cap engaging edge of the fulcrum member and around the rounded nose thereof; and a cap engaging jaw beneath said fulcrum.

2. An uncapping tool stamped from a single piece of sheet metal; and comprising a flat body portion adapted to be edgewise disposed, said body portion having a hole in the rear end thereof; a flat cap engaging jaw formed from a curved protuberance of metal; a flat fulcrum adapted to rest edgewise on a cap to be removed, said fulcrum having a rounded nose; and a flange projecting at right angles from said fulcrum to strengthen it and provide a flat bearing surface therefor, said flange being continued around the edge of the tool and terminating in a squared end which is adapted to supplement the cap engaging jaw.

3. In an uncapping tool; an operating end comprising a flat edgewise disposed fulcrum member; a flange integral with said fulcrum member and extending at right angles therefrom, said flange extending along the cap engaging edge of the fulcrum member to strengthen the fulcrum member and form a relatively large bearing surface on the top of a cap to be removed; and a cap engaging jaw beneath said fulcrum.

4. In an uncapping tool; a flat jaw positioned edgewise with respect to a cap to be removed; and a flange projecting at right angles from said jaw at the end thereof, said flange forming a narrow engaging surface adapted to contact tangentially with a side sealed container and obtain a firm bite on the gasket at a point contiguous to the container.

5. In an uncapping tool, an operating end comprising an edgewise disposed fulcrum member, a flange integral with said fulcrum member and extending laterally therefrom to strengthen the fulcrum member and to form a relatively large bearing surface on the top of the cap to be removed, a cap engaging jaw beneath said fulcrum member edgewise disposed with respect to a cap to be removed, and a flange projecting laterally from said jaw to form a narrow engaging

- surface adapted to contact tangentially with a cap on a container at a point contiguous to the container.
6. In an uncapping tool of the class described, the combination of a substantially flat jaw positioned edgewise with respect to a cap to be removed, and a flange projecting laterally from said jaw to strengthen said jaw and to form a relatively wide en-
10 gaging surface adapted to engage a cap tangentially of a container.
7. In an uncapping tool of the class de-
scribed, an operating end comprising a sub-
stantially flat edgewise disposed fulcrum
member, an integral flange extending later-
ally from said edgewise disposed fulcrum
member to strengthen the fulcrum and to
form a relatively large bearing surface
adapted to rest on the top of the cap, and a
cap engaging jaw beneath said fulcrum. 15

JAMES S. HARDIMAN.
